TYPEWRITING MACHINE

William F. Helmond, West Hartford, Conn., assignor to Underwood Elliott Fisher Company, New York, N. Y., a corporation of Delaware

Original application December 2, 1933, Serial No. 700,646. Divided and this application January 16, 1937, Serial No. 120,850

9 Claims. (Cl. 197—149)

This invention relates to improved means for adjusting the platen toward or from the normal printing-plane of the types, in accordance with the number of work-sheets being typed upon. The improved platen-adjusting means include a front and center part of a fore-and-aft shiftable platen-carriage support, said part forming an adjustable abutment which follows a cam mounted on a shaft reaching to the outer side of the machine, where said shaft presents a handle by which it may be manipulated. Springs force the carriage so that said cam-following abutment always bears against the cam, whereby the position of the carriage-support and hence of the platen depends on the angular position of said cam-shaft as determined by said handle and a co-operative detent.

The guiding of the front part of said carriage-support may be effected in a known manner. At the rear portion of the slidable support, improved means are employed for slidably guiding said rear portion, to the end that requisite alignment of the rear of the slidable support and rear guiding means may be facilitated and the parts constituting such rear guiding means simplified.

This application is a division of my application Serial No. 700,646, filed December 2, 1933, (now Patent No. 2,074,333, dated March 23, 1937).

Other features and advantages will hereinafter appear.

In the accompanying drawings,

Figure 1 is a fragmentary side elevation view, showing details of the improvements for guiding the carriage-support at its rear for fore-and-aft adjustment.

Figure 2 is a cross-sectional side elevational view of a noiseless typewriter, the section being taken through the middle of the machine, and showing the rotatable cam and the related parts effecting an adjustment of the platen.

Figure 3 is a top plan view, showing details of the improved means for guiding the platen-carriage support at its rear portion for fore-and-aft adjustment in accordance with the number of work-sheets on the platen. The view also shows details of the improved means manually operable for making the carriage-support adjustment.

Figure 4 is a fragmentary side view, showing arrangement of a handle and detent whereby the carriage-support adjustment is manipulated and gaged.

Figure 5 is a side elevation view of the typewriter, incorporating the improved carriage-support adjustment.

The invention is applied to a noiseless typewriter such as shown in the patent to Going 1,632,330 of August 28, 1928, and includes type-keys 24 operable to move upper and lower case types 26 and 27 to print upon a platen 24.

In Figures 2 and 3 there is shown a cross-bar or platform 43 fastened by screws 44 to side-members 45 of the machine-frame 15. Upon said platform 43 rests a bolster 47, which supports a platen-carriage 40 by means of a rock-shaft 48, journaled in lugs 49 of said bolster. Arms 50 of said rock-shaft 48 enable the latter, when operated by a case-shift key-train, not shown herein but described in Patent No. 1,661,799, dated March 6, 1928, to Going, to raise and lower a track-bar 51 along which the platen-carriage 40 runs.

The bolster 47 extends from side to side of the machine-frame 15, see Figure 3, and is guided for fore-and-aft adjustment of the platen on a slight incline. Fore-and-aft adjusting movement of the bolster is effected by improved means, which will be described later, and which are manipulatable for the usual purpose of bringing the platen forward or rearward, in accordance with the number of superposed work-sheets positioned around the platen, it being understood that the type-carriers 20 have the limited printing-motion which is characteristic of printing quietly by pressure.

Only the middle portion of the bolster 47 rests directly upon the platform 43, as at 52, the end bolster-portions being above raised seats 53 at the ends of the platform 43, and bearing against said seats by means of screw-studs 54, adjustable in the bolster for the purpose of properly seating the bolster on said platform 43. To retain the bolster 47 against upward displacement, said bolster has a forwardly-projecting ledge 56 slidably abutting an overlying segment 57, which also supports the mountings (not shown) for the type-bars 20. The segment 57 has arms 60, (Figures 2 and 3, whereby said segment is secured to the platform 43 by screws 61. The bolster-ledge 56 is of such length as to slidably fit between the segment-arms 60, the bolster being thereby retained at its front portion against lateral displacement. The bolster extends substantially toward the rear of the machine. At the middle portion thereof the bolster 47 extends rearwardly and upwardly forming a transverse wall 91 joined to rearwardly-turned side-walls 92 to form a channel 93. The usual rail 230 of the carriage is shown to bear against the wall 91 of the bolster 47 to support the carriage as the types 26 or 27

print by pressure against the platen 24. The upper part of the transverse wall 91 has a recess 94 to admit a forwardly-reaching tongue, which forms a counter-stop 95, co-operative with margin-stops 96 of the carriage 40. Said tongue or stop 95 is bent forwardly from an arm 97, which is seen edgewise, and is only shown in such part in Figure 2 as to indicate its improved form. The operation of said arm 97 for margin-releasing and key-locking may be effected by means of parts, not shown, but which may be along the lines used in prior machines and described in Patent 1,255,571, to Anderson, dated February 5, 1918. The side-walls 92 extend under a tabulator stop-rack 98 and have flanges 101 to which is attached, by screws 102, a column-like housing 103 which supports parts of a novel tabulating mechanism fully described in my original application of December 2, 1933, Serial No. 20 700,646, now Patent 2,074,333, dated March 23, 1937.

It will be seen now that the bolster 47 and some of the parts supported overhang the bolster-supporting platform 43 rearwardly to a substantial extent. In addition, therefore, to supporting and slidably guiding the bolster 47 at its forward portion by means of the platform 43, the segment 57, the segment-arms 60, and the bolster-studs 54 bearing on the platform-seats 53, the platform-overhanging portion of the bolster is also supported vertically and laterally and slidably guided by novel means organized as an improvement over bolster-guiding means employed in previous machines and which novel means will now be described.

Joined to the rear portions of the machine-frame side-members 45 is a cross-plate 105 clearing the tabulator-mechanism housing 103 as at 106, Figure 2, but rising at the sides of said 20 housing to present lugs 107 extended forwardly, and inwardly toward one another, to underlie edges 108, Figure 1, of the side-walls 92 which form the channel 93 of the bolster. Said lugs 107 have adjustable studs 109 against which 25 the edges 108 slidably abut, said edges extending in the direction in which the bolster 47 is adjusted fore and aft. The adjustment of the studs 109 compensates for variations in the height of said edges 108 due to manufacturing 30 tolerances. The cross plate 105 is also extended upwardly to present lugs 111 opposite the outer sides of the side-walls 92. There is secured to each wall 92 a plate or keeper 112 which, by reason of elongate screw-holes 113 therein, is adjustable in the direction in which the studs 109 are 35 adjusted, keeper-fastening screws 114 passing through said elongate holes 113. Each keeper 112 has a slot 115 whose edges extend parallel to the side-wall edges 108 and slidably fit the inner 40 end 116 of a screw-stud 117 threaded crosswise of the lug 111 as seen in Figure 3. The keepers 112 and crosswise extending screw-studs 117 thus co-operate with the edges 108 and studs 109 to retain the rear portion of the bolster against 45 vertical displacement, and said screw-studs 117 also retain the rear portion of the bolster against lateral displacement, the screw-studs being micrometrically adjustable endwise to abut the side-walls 92 to take up all lateral play at the 50 rear of the bolster 47. For such endwise abutment with said bolster-side walls 92, the screw-studs 117 may have flanges 119 which bear against the outer sides of the plates 112. Set-screws 120 hold the screw-studs 117 in adjusted 55 positions and lock-nuts 121 maintain the adjust-

ment of the studs 109. It will be seen now that the parts for slidably supporting the platform-overhanging portion of the bolster are of simple and inexpensive character and may nevertheless be easily manipulated and afford micrometric adjustments in all necessary directions in order to free the front portion of the bolster from liability of binding in the guiding means afforded by the platform 43 and related guiding parts for the front of the bolster.

In adjusting the described means whereby the platform-overhanging portion of the bolster is slidably guided, the procedure is preferably as follows: With the screws 114 loosened for both keepers 112, the screw-studs 109 are raised or lowered by turning them micrometrically until the bolster moves without binding in the guides afforded by the platform 43 and related parts. The lock-nuts 121 are then tightened. The screw-studs 117 are then moved in or out to micrometrically take up all lateral play at the rear portion of the bolster 47, it being understood that for this purpose the screw-stud flanges 119 bear against the keepers or plates 112. The latter are then tightened in such position by their screws 114 that the lower edges of their slots 115 slidably abut the peripheries of inner ends 116 of the screw-studs 117, thereby retaining the rear end of the platform-overhanging portion of the bolster against upward displacement. The screw-studs 117 are then locked by the set-screws 120. It will be understood that, after these adjustments have been made, the screw-studs 109 remain in abutment with the bolster-edges 108, and are not backed off from the latter, since it is not desired that the upper edges of the keeper-slots 115 be depended on to support the bolster.

Referring now to the improved means for shifting the bolster 47 for platen-position adjustment, a cam-shaft 123 extends from the middle of the machine toward and through the machine-frame side-member 45 to present at the side of the latter a handle or crank 124 for manually rotating said cam-shaft. At the middle of the machine the cam-shaft 123 has fastened thereto or formed integrally therewith a cam 125. It is desired that means for journaling the cam-shaft 123 at its crank-end and retaining it endwise, and means for releasably detenting the cam-shaft 50 in different angular positions be combined in a unitary assembly easily placeable in or removable from the machine, in order to reduce manufacturing and servicing costs; and to these ends the following construction may be employed.

Fastened to the top of the side-members 45 by screws 129, and forming part of the frame 15, are plates 130 extending inwardly toward one another, and rigidly joined to a yoke 131 to form a bridge, which supports a type-guide 132, Figure 2. At the middle portion of the yoke 131 of the bridge, there is a pair of lugs 133, 134, for journaling the cam-shaft 123 at points contiguous to the cam 125. The lug 133 gives a full bearing for an inner end 135 of the cam-shaft, 60 but, as indicated in Figures 2 and 3, the other lug, 134, bears only part way around the back of the cam-shaft in order to permit the cam-shaft 123 to be withdrawn or entered endwise without interference between the cam 125 and lug 134, the bolster 47 being movable forward a little to enable the cam 125 to pass the lug 134. A block 126, embodying said lugs 133, 134, is fastened to the yoke 131 by screws 127.

At the crank-end of the cam-shaft, the latter

is journaled in a hub 136 of a plate 137, fastened to the outer side of the side-member 45 by screw 139. The crank 124 is fastened to the cam-shaft 123, and carries at its end a knob 140 spring pressed and mounted as shown in Figure 3, said knob having a stem 141, which may be entered in or withdrawn from any one of a series of holes 142 located in the plate 137 to determine and maintain different angular positions 10 of the cam-shaft 123. The latter is maintained against endwise displacement, when the parts are positioned in the machine, by abutment of the crank 124 with the outer end of the hub 136, and by abutment of a shaft-collar 143 with the 15 inner end of the hub. The plate 137 may have stops 144 to limit the swing of the crank 124 in opposite directions.

It will be seen now that the described parts at the crank-end of the cam-shaft are together 20 with the cam-shaft 123 and its cam 125, assembled as a unit which is easily placed in the machine and easily removed therefrom.

The bolster 47 has an abutment bearing on the cam 125, said abutment being preferably 25 in the form of a screw 146 threaded in a plate 147 fastened to the bolster 47 by screws 148. The end of the abutment-screw 146, and therefore the bolster 47, follows the cam 125, inasmuch as said bolster is pressed rearwardly, toward the 30 cam 125, by suitable springs such as leaf-springs 149 fastened at one end to the key-lever bar 73 by screws 151, the other ends of the springs 149 pressing upon studs 152 of the bolster which also prevent the leaf-springs from turning.

35 For single work-sheet typing, the cam-shaft 123 is in such angular position, as seen in Figure 2, that the highest point of the cam 125 is opposite the abutment-screw 146. In correspondence with said primary angular position 40 of the cam-shaft, said abutment-screw 146 will have been initially adjusted to bring the printing-face of the platen 24 to such position that the types 26, 27 make proper impression upon the single work-sheet. With the cam-shaft 123 thus 45 set for normal or single-sheet printing-position, the stem 141 of the crank 124 will be in the first hole 145 of the detent-plate 137.

It will be seen now that as the cam-shaft crank 123 is rotated from the first hole 145 to other 50 hole-positions, the cam 125 will be rotated clockwise of Figure 2, thereby causing the bolster 47 and hence the platen 24 to be shifted rearwardly under the influence of the bolster-springs 149, the extent of the rearward shift depending on the 55 contour of the cam 125, and its angular position as determined by means of the detent-holes 162. It will also be seen that as the cam-shaft 123 is rotated counterclockwise from any hole 142 other than the first hole 145, the cam 125 will force 60 the bolster forwardly against the pressure of the springs 149, thereby also bringing the platen forwardly.

65 The improvements in the means for adjusting the platen 24 afford important benefits, it being noted that said platen-adjusting means are simple in character, and nevertheless efficient in operation.

Variations may be resorted to within the scope 70 of the invention, and portions of the improvements may be used without others.

Having thus described my invention, I claim:

1. In a typewriting machine, the combination with the machine-frame, a platen, types having a limited throw toward the platen, a platen-carriage, and a bolster mounting said carriage,

said bolster mounted in said frame for fore-and-aft movement for regulating the platen-position relative to the printing-plane of said types, of a bolster-adjusting cam-shaft extending crosswise of the machine to project an end through the side of said frame for manual rotation of said shaft, a single cam connected to the said shaft and engaging the said bolster substantially midway between the sides of the frame, and a bridge supported by said frame and affording a firmly fixed bearing for said shaft contiguous to said camming-connection, whereby, by varying the angular position of said cam-shaft having said single camming-connection to the bolster, said position of the platen relative to the printing-plane of the types is determinable in accordance with the number of work-sheets on the platen.

2. In a typewriting machine, the combination with the machine-frame, a platen, types having a limited throw toward the platen, a platen-carriage, and a bolster mounting said carriage, said bolster mounted in said frame for fore-and-aft movement for regulating the platen-position relative to the printing-plane of said types, of a bolster-adjusting cam-shaft extending crosswise of the machine to project an end through the side of said frame for manual rotation of said shaft, said shaft having a single peripheral cam located substantially midway between the sides of said frame, said bolster having an abutment for following the cam and being spring-pressed toward said cam, and a bearing supported by said frame and journaling said cam-shaft at a point contiguous to said cam and so that said cam-shaft may be entered or withdrawn endwise into or from said bearing through said side of the frame in which said shaft is also journaled, whereby, by varying the angular position of said cam-shaft having said single cam, said position of the platen relative to the printing-plane of the types is determinable in accordance with the number of work-sheets on the platen.

3. The invention as set forth in claim 2, said cam-following abutment being screw threaded in the bolster to bear endwise on said cam, said screw being adjustable to initially adjust the bolster and therefore the platen relatively to a primary position of the cam-shaft.

4. The invention as set forth in claim 2, said side of the frame having removably fastened thereto a member in which said shaft is journaled, and against which said shaft bears for retention endwise, said shaft having a crank arranged to releasably engage said member at different stations, to thereby hold the shaft in different angular positions, said member, shaft and crank forming a preassembled unit readily placeable in or detachable from the machine.

5. In a typewriting machine having a platen-carriage bolster adjustable fore and aft relatively to the printing-plane of the types, and fixed guides presented by the machine-frame-work to slidably mount and retain said bolster against vertical and lateral displacement at its front portion; micrometrically-adjustable means for guiding the rear portion of said bolster which extends beyond and overhangs said guides, said means including, in combination, devices screw-controlled for micrometric adjustment in height and on which said rear bolster-portion slidably rests, and devices engaging opposite sides of said rear bolster-portion and screw-controlled for micrometric adjustment to take up side play, whereby the position of said rear overhanging bolster-portion may be finely and quickly ad-

justed laterally and vertically to secure free movement of the front bolster-portion in said fixed guides.

6. In a typewriting machine having a platen-
5 carriage bolster adjustable fore and aft relatively to the printing-plane of the types, and fixed guides presented by the machine-framework to slidably mount and retain said bolster against vertical and lateral displacement at its front portion;
10 micrometrically-adjustable means for guiding the rear portion of said bolster which extends beyond and overhangs said guides, said means including, in combination, upstanding laterally-spaced screw-studs mounted at the rear of the
15 machine-frame, said rear bolster-portion slidably resting on said studs, and a pair of transversely-extending screw-studs also mounted at the rear of said frame and bearing against opposite sides of said rear bolster-portion to take up
20 lateral play, said upstanding and said transverse screw-studs being micrometrically adjustable to respectively seat the rear overhanging bolster-portion at such elevation and to guide the same laterally without play so as to secure
25 free movement of the front portion of the bolster in said fixed guides.

7. In a typewriting machine having a platen-carriage bolster adjustable fore and aft relatively to the printing-plane of the types, and
30 fixed guides presented by the machine-framework to slidably mount and retain said bolster against vertical and lateral displacement at its front portion; micrometrically-adjustable means for guiding the rear portion of said bolster which
35 extends beyond and overhangs said guides, said means including, in combination, upstanding laterally-spaced screw-studs mounted at the rear of the machine-frame, said rear bolster-portion slidably resting on said studs, a pair of trans-
40 versely-extending screw-studs also mounted at the rear of said frame and bearing against opposite sides of said rear bolster-portion to take up lateral play, said upstanding and said transverse screw-studs being micrometrically adjust-
45 able to respectively seat the rear overhanging bolster-portion at such elevation and to guide the same laterally without play so as to secure free movement of the front portion of the bolster in said fixed guides, and keepers shiftably secured

to the sides of said rear bolster-portion to contact said transverse studs peripherally, and thereby retain the rear bolster-portion against upward displacement.

8. In a typewriting machine, the combination 5 with a machine-frame, a work-sheet supporting platen, types having a controlled throw toward the platen, a platen-carriage, and a bolster mounting said carriage, of means for adjusting the position of the bolster and therefore the 10 position of the platen relatively to the printing plane of the said types in accordance with the number of sheets to be typed upon, said means including a cam, a rotatable shaft mounted upon the machine-frame bearing the said cam, an ad- 15 justing crank for the said shaft, means to de- tent said shaft and therefore also the cam in a number of crank-adjusted positions including a primary position, and supplemental adjustable means associated with the said cam for also ad- 20 justing the position of the platen relatively to the printing plane, whereby, in effecting a sup- 25 plemental adjustment, the proper printing rela- 30 tion can be established between the platen and the printing plane, for typing upon a single sheet 35 with the said cam set to primary position.

9. In a typewriting machine, the combination 30 with a machine-frame, a platen, types having a controlled throw toward the platen, a platen-carriage and a bolster mounting said carriage, 35 said bolster mounted in said frame for fore-and-aft movement for regulating the platen-position relative to the printing-plane of said types, of a bolster-adjusting cam located substantially mid-ways between the sides of said frame, a shaft 40 upon which said cam is mounted, said shaft being settable to different angular positions including a primary position, a frame-supported bridge, affording a fixed bearing for said cam-shaft con- 45 tinuous to the said cam and an adjustable cam- 50 engaging abutment on the said bolster, whereby the bolster and consequently the platen can be adjusted relative to the printing plane, and to the said primary position of the cam, by adjusting the said abutment, and whereby the position of the said platen, relative to the said printing plane, is determinable in accordance with the number of sheets on the platen, by setting the cam-shaft.

WILLIAM F. HELMOND.
